UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

DESIGN FOR A HANDLE FOR A SCREW-DRIVER OR SIMILAR ARTICLE.

54,142.

Specification for Design.

Patented Nov. 4, 1919.

Application filed January 12, 1917. Serial No. 142,113. Term of patent 14 years.

To all whom it may concern:

Be it known that I, JOHN L. SOMMER, a citizen of the United States, residing at Newark, in the county of Essex and State of New Jersey, have invented a new, original, and ornamental Design for a Handle for a Screw-Driver or Similar Article, of which the following is a specification, reference being had to the accompanying drawing, forming part thereof.

Figure 1 is a side view illustrating my new design, and

Fig. 2 is an edge view.

I claim:

The ornamental design for a handle for a screw-driver or similar article as shown.

JOHN L. SOMMER.
